Primary Examiner — Elizabeth Albert*Assistant Examiner* — Kelley Donnelly(74) *Attorney, Agent, or Firm* — Lerner, David, Littenberg, Krumholz & Mentlik, LLP(57) **CLAIM**

The ornamental design for audio video shelving unit, as shown and described.

DESCRIPTION

FIG. 1 is a front perspective view of the subject audio video shelving unit;

FIG. 2 is a front view thereof;

FIG. 3 is a rear view thereof;

FIG. 4 is a top plan view thereof; and,

FIG. 5 is a right side view thereof (the left side view is a mirror image of the right side view).

The broken lines of the openings on the rear support panel in FIGS. 1, 2, and 3 are shown for the purpose of illustrating the environment of the “audio video shelving unit” only and form no part of the claimed design.
